UNITED STATES PATENT OFFICE

FREDERICK G. CORBUS, OF PHILADELPHIA, PENNSYLVANIA, ASSIGNOR TO DAVID M. NEWBOLD, OF PHILADELPHIA, PENNSYLVANIA

WATER HEATER

Application filed August 16, 1928. Serial No. 300,050.

This invention relates to improvements in water heaters, and more particularly to the construction of the dome of the combustion chamber of such heaters.

Attempts have been made to provide the dome or header for the combustion chamber of heaters of this character, when made of steel, with auxiliary heating means consisting of a number of studs or projections distributed either regularly or at random, throughout the surface of the dome on both sides thereof, and therefore extending partly into the combustion chamber, and partly into the water space or tank. In steel headers or domes, so far as I am aware, the studs have extended through the dome, making it necessary to perforate it, the method of securing the studs being by riveting them or securing them by jamb nuts or providing the studs with threads, cooperating with threads in the dome, and in some cases it appears that the studs have apparently been driven in the dome with a tight fit, but in no case, so far as I am aware, have these studs been secured to the dome by welding, electrically or otherwise. None of the methods heretofore employed have been successful, due to the fact that where the studs pass through the dome and are secured by methods other than welding, the effect is that the dome is perforated and such perforations are not effectively closed by the studs and due to the expansion and contraction of the metal of which the dome is made, and the studs or projections are made, leaks have invariably occurred to a greater or less extent, according to the manner or method of attachment of the plugs.

In my co-pending application Serial Number 221,069, filed September 21, 1927, I have shown a method of applying these studs to the dome of the combustion chamber by a swaging or riveting process and notwithstanding the fact that the metal employed for the manufacture of the studs has, as stated in said application, the same coefficient of expansion as the material of the dome, trouble has been experienced from leaks.

In an apparatus of this kind, it is obvious

that unless the dome or metal separating the combustion chamber from the water tank is absolutely leakless, the efficient operation of the device is impossible. In view of the foregoing, and to overcome the objections intimated, I have devised a construction wherein these studs may be attached to both sides of the dome, without the necessity of perforating the metal of the dome, and test has demonstrated that an absolutely leakless structure is provided, and even where the dome is perforated or punctured, and the studs passed through the perforations and welded, satisfactory results may be attained, the difference between the degrees of success being due to the fact that the studs are welded to the dome and both being constructed of metal having the same coefficient of expansion, become virtually and substantially integral.

In view of the foregoing, the invention contemplates the provision of a dome having spotwelded thereto on both sides thereof, preferably, a number of studs or projections, those on the bottom extending into the combustion chamber and those above extending into the tank, the studs being of the same material as the dome and having the same coefficient of expansion, so that under operative conditions involving expansion and contraction, the homogeneity of the studs and dome eliminates the tendency of separation of these parts, thus eliminating the possibility of leaks. Secondarily, the invention contemplates the use of studs that may extend through the material of the dome, but which may be welded in position therein.

In the drawings illustrating the invention—

Figure 1 is a view partially in section and partially in elevation of a water heater having a dome embodying my invention.

Figure 2 is a detail perspective view of one of the heat augmenting studs or elements.

Figure 3 is a similar view of a modified form of said element, used upon the top surface of the dome.

Figure 4 is a detail sectional view of a portion of the dome showing the form of

stud shown in Figure 3 on the upper surface of the dome, and a stud like that shown in Figure 2 on the lower surface.

Figure 5 is a view showing portions of 5 the arms and the electrodes of a spot welding machine, by which the studs or projections are welded to the dome plate.

Referring to the drawings, the numeral 1 10 designates the outer casing, 2 the wall of the water tank, there being between the two 15 walls a filling of insulating material 3, of asbestos or the like, the filling forming an insulating jacket. The lower end of the tank is closed by a cap 4, with the exception 20 of a suitable number of holes 4' for the purpose of admitting air to the burner.

The numeral 5 designates the dome of the combustion chamber 6, which chamber is formed by the bottom of the tank, and the 25 said dome, and contains a gas burner 7 of any approved type, the burner being supplied by a pipe 8 connected in the usual way with a suitable thermostat 9 employed to regulate the flow of gas to the heater, according 30 to the temperatures desired. The thermostat and its connections, burner, etc., form no part of the invention, and need not be further considered.

Let into the dome at proper places, are a 35 number of heat conducting tubes or flues 10 which extend entirely to the top of the tank, the tubes being open at their tops and bottoms, there being provided in the top of the heater, means for conducting the products 40 of combustion to a single outlet, which may be of usual form and which is not shown. As shown in Figure 1 baffles 11 may be employed in the form of undulated metal strips that are suitably supported, preferably 45 at the top of the tubes and extend substantially throughout the length of the tubes, these being for the purpose of retarding or baffling the too rapid flow of heat through the tubes for the obvious purpose of utilizing the heat for the more rapid heating of the water.

The numeral 12 designates a plurality of studs and in the form shown in Figure 1 of the drawing, these will usually be identical 50 both for the top of the dome and the under side thereof. As shown in Figure 2, these studs or projections are normally slightly rounded at their blunt ends, which rounded portion is obliterated or fused away in the 55 process or method of attaching them to the surface of the dome, when the welding current is applied. These studs or projections are numerous and are distributed throughout virtually the entire surface of the dome, 60 both at the bottom and top thereof. The lower studs extend into the combustion chamber 6 in position to contact with the flame of the burners and the upper studs extend into the water space of the tank 2. 65 Preferably these bottom and top studs are in

line with each other and in the welding process will be simultaneously welded in the dome.

Referring to Figure 5, "A" designates the upper arm of an approved spotwelding machine, and "B" the lower arm, to which are attached respectively, the electrodes "C" and "D." One or both of the arms "A" and "B" and the electrodes carried thereby are capable of a wide range of separation from the other, so that after the studs are welded to the dome, the electrodes are withdrawn from said studs.

Referring to Figure 4 it will be noted that the lower stud corresponds with those on 80 the under side of the dome in Figure 1, whereas the upper stud is different, the latter consisting of a short hollow, tapered pipe section 13, of the same general external shape as the studs 12. The pipe sections are 85 open at their upper ends, as indicated at 14 and extending into the water chamber of the burner, are at all times, during the operation of the heater, filled with water, thus providing an additional heating surface 90 composed of the inner and outer surfaces of the pipe sections.

As shown in Figure 4, the hollow studs are spot welded to the dome, preferably at the same time the stud or projection is welded to the lower surface of the dome.

It will be noted by reference to Figures 3 and 4, that the modified form of stud for use on the upper surface of the dome, is as intimated, of the same general external shape as the lower studs, thus enabling electrodes of the same shape to be used in welding both forms.

From the foregoing, it will be seen that the preferred construction and method described, eliminates the necessity of perforating the dome, thus providing an efficient heat augmenting means whereby the heat is conducted from the combustion chamber to the water in the tank, and greatly augmented 105 by reason of the increased heating surface in both the chamber and the tank.

Having thus described my invention, what I claim is:

1. A heater of the class described, comprising a tank closed at its top and bottom, a combustion chamber below the tank including an imperforate dome forming a closure for the bottom of the tank, said dome being provided with numerous studs spot-welded on the upper and lower surfaces thereof, and in vertical line with each other, and forming heat augmenting means, and means for supplying heat to said combustion chamber.

2. A heater of the class described, comprising a tank closed at its bottom and top, a combustion chamber below the tank including an imperforate dome forming a closure for the bottom of the tank, said

dome being provided on its upper side with numerous hollow studs open at their upper ends, said studs being welded to the dome surface, and means for supplying heat to
5 the combustion chamber.

In testimony whereof I affix my signature.

FREDERICK G. CORBUS.
